PUMP PLUNGER

George A. Hatfield, Torrance, Calif., assignor to
The National Superior Company, Toledo, Ohio,
a corporation of Delaware

Application July 30, 1935, Serial No. 33,837

8 Claims. (Cl. 309—33)

This invention relates to pump plungers, and more particularly to an improved packing means applicable for application to reciprocating pump pistons, particularly that type of piston commonly known as a pump plunger and as employed from 5 in oil well pump barrels that are suspended from a well tubing positioned within the well hole.

In the operation of oil well pumps, the reciprocation of the plunger is usually effected by sucker rods. In deep wells ranging from 4,000 to 8,000 10 feet in depth, it has been found through experience that a deep well plunger equipped with a conventional leather or composition packing cup will only operate for a comparatively short 15 period before the packing cups are completely destroyed or rendered incapable of providing an adequate seal between the plunger and working barrel.

It is an object of my invention to provide an 20 improved packing unit applicable for use upon a pump plunger employing a packing cup reinforced to withstand the high pressures incident to the increased hydrostatic and velocity heads occasioned through the use of such pump plungers in deep wells.

Other objects and advantages of this invention it is believed will be apparent from the following detailed description of a preferred embodiment thereof as illustrated in the accompanying drawing.

In the drawing:

Figure 1 is a cross-sectional view of a deep well pump having a pump plunger equipped with packing cup units embodying my invention.

Figure 2 is an enlarged fragmental cross-sectional elevation illustrating one of the packing cup units when new.

Figure 3 is an enlarged fragmental cross-sectional elevation showing the packing cup in its 40 sealed position after it has been worn in service.

Figure 4 is a similar view illustrating the worn cup shown in Figure 3 when the fluid pressure is removed.

Figure 5 is a similar view of a packing cup 45 that has been worn to a point where it is rendered incapable of further use.

Figure 6 is an enlarged cross-sectional elevation illustrating the packing cup embodying my invention adapted to a different type of pump plunger.

Figure 7 is an enlarged fragmental cross-sectional elevation illustrating the packing cup embodying my invention adapted to a third type of pump plunger.

55 In the drawing I have illustrated my invention as adapted to a well pump of the travelling plunger type for the purposes of illustration only. In this illustration 1 indicates a well tubing from which there is suspended a working barrel 2. A standing valve 3 is seated upon a

shoe 4 attached to the lower end of the barrel 2. A pump plunger assembly 5 is fitted within the barrel 2 and is connected to sucker rods 6 which extend to the surface of the well and provide the connecting means through the medium 5 of which the pump plunger 5 is reciprocated in the pump barrel 2.

A traveling valve 7 is provided in the plunger assembly 5 to permit the free passage of fluid through the plunger on the downstroke of the 10 plunger and prevent the return flow of the fluid through the plunger on the pumping or up-stroke thereof. The particular construction of the plunger is common in the art and may be of any 15 of the many different forms now commonly utilized in the art. The plunger assembly as herein illustrated includes a mandrel 8, upon which the packing cups 9 are mounted in position to contact the inner wall of the pump barrel 2 and provide a fluid-tight seal between the plunger 5 20 and the barrel 2. The cups 9 may be formed of leather or any suitable molded composite material such, for example, as vulcanized rubber and duck fabric.

In the embodiment of my invention illustrated 25 in Figures 1 to 5, inclusive, the cups 9 are spaced along the mandrel 8 by means of cup rings 10 and cup followers 11. The lower end of each cup 9 has a reduced annular section 12 which is clamped between a ring 10 and a follower 11. 30 The upper portion 13 and the lower portion 12 of the cups 9 and the follower 11 cooperate to define an annular recess 14 to receive a reinforcing or armor ring 15.

The armor ring 15 is so proportioned in length 35 and external diameter as to have a free-floating action within the barrel 2. The free-floating action is desirable to permit the armor ring 15 a freedom of movement to compensate for the eccentricity of the pump barrel 2 usually occasioned 40 in wells due to the fact that very few, if any, well holes are straight holes.

In the particular packing unit that acts to form a seal between the plunger and the plunger barrel, the fluid being pumped enters the space 16 45 between the cup 9 and the cup ring 10 and expands the upper portion 13 of the cup into sealing engagement with the wall of the pump barrel 2.

Figures 3, 4, and 5 illustrate the operation of 50 the cups 9 under conditions of wear occasioned from the continual reciprocation of the cups 9 within the pump barrel 2. The position of greatest wearing friction between the cups 9 and the inner barrel 2 is as illustrated at a point spaced a distance above the armor ring 15.

55 It will be obvious from a consideration of the foregoing that the armor ring 15 acts to prevent collapse or buckling of the cup 9 under high fluid pressure by reinforcing the cup immediately adjacent the upper or sealing portion 13 of the 60

cup 9. The armor ring 15 is furthermore capable of floating radially of the plunger to thereby adjust itself relative to the sealing portion of the cup 9 independently of any tendency of the mandrel 8 to become misaligned with respect to the axis of the barrel 2.

In Figure 6 I have illustrated a modification of my invention in which the rings 10^a are assembled end to end by means of a threaded connection 17^a to form a pump plunger assembly 5^a independently of a mandrel. In this modification each ring 10^a is formed at its upper end 11^a to cooperate with the lower end of the next adjacent ring 10^a to clamp the packing cups 9^a into position. In this modification the armor ring 15^a surrounds each cup 9^a and functions in every way the same as does the armor ring 15 set forth in connection with the illustration of my invention shown in Figures 1 to 5, inclusive.

20 In Figure 7 I have illustrated a further modification of my invention wherein the rings 10^b and cup followers 11^b are assembled on a mandrel 8^b.

Each follower 11^b is formed with an annular groove 18^b to receive a complementary annular tongue 19^b formed on the lower end of each cup 9^b. The cup 9^b being semi-flexible can be sufficiently distorted to cause the tongue 19^b to snap into the groove 18^b. With the cup 9^b mounted 30 on the follower 11^b, the ring 10^b is pressed into position and acts to prevent the cup being withdrawn in service. As in the other modification of my invention, an armor ring 15^b surrounds each cup 9^b and functions in the same manner 35 as in the other modifications of my invention hereinabove set forth.

Having fully described my invention, it is to be understood that I do not wish to be limited to the details herein set forth, but my invention 40 is of the full scope of the appended claims.

I claim:

1. In a packing assembly for a plunger, the combination of an annular resilient packing element having a sealing portion adapted to be expanded into sealing engagement with the wall of an encircling cylinder, means to secure said element to the plunger, and a reinforcing ring encircling said element below the sealing portion thereof, said ring having limited radial freedom 45 independent of the plunger to adjust itself with respect to the sealing portion of said element.

2. In a packing assembly for a plunger, the combination of an annular resilient packing element having a sealing portion adapted to be expanded into sealing engagement with the wall of an encircling cylinder, means to secure said element to the plunger, and means independent of the latter said means encircling said element intermediately thereof to confine the radial expansion of said element immediately adjacent the sealing portion thereof.

3. In a device of the character described for relative reciprocation within a cylinder, the combination of a plunger mounted within the cylinder, an annular resilient packing element having a sealing portion adapted to be expanded into sealing engagement with the inner wall of the cylinder, means to secure the packing element to the plunger, and means independent of the latter said means encircling the packing element adjacent to the securing means to confine the radial expansion of the packing element immediately adjacent the sealing portion thereof.

4. In a device of the class described, for relative reciprocation within a cylinder the combination of a pump plunger mounted within the cylinder, an annular resilient packing element having a sealing portion adapted to be expanded into sealing engagement with the inner wall of the cylinder, means for securing the packing element at one end to the plunger, and means independent of the latter said means and spaced in position adjacent the secured end thereof to confine the radial expansion of the packing element immediately adjacent the sealing portion thereof. 5

5. In a device of the class described, for relative reciprocation within a cylinder the combination of a pump plunger mounted within the cylinder, 15 an annular resilient packing element having a sealing portion adapted to be expanded into sealing engagement with the inner wall of the cylinder, means for securing the packing element at one end to the plunger, and means independent 20 of the latter said means and spaced in position adjacent the secured end thereof to confine the radial expansion of the packing element immediately adjacent the sealing portion thereof, and said latter means having a limited radial freedom 25 independent of the plunger to permit adjustment with respect to the sealing portion of said packing element.

6. In a device of the character described for relative reciprocation within a cylinder, the combination of a plunger mounted within the cylinder, an annular resilient packing element mounted between the plunger and the cylinder and having a sealing portion adapted to be expanded into sealing engagement with the wall of the cylinder, locking means for securing the packing element to the plunger, and an armor ring encircling the packing element adjacent the locking means to confine the radial expansion of the packing element immediately adjacent the sealing portion thereof. 30

7. In a device of the character described for a relative reciprocation within a cylinder, the combination of a plunger mounted within the cylinder, an annular resilient packing element mounted between the plunger and the cylinder and having a sealing portion adapted to be expanded into sealing engagement with the wall of the cylinder, locking means for securing the packing element to the plunger, an armor ring encircling the packing element adjacent the locking means to confine the radial expansion of the packing element immediately adjacent the sealing portion thereof, and said armor ring being so formed and proportioned as to permit limited radial freedom independent of the plunger to permit the armor ring to adjust itself with respect to the sealing portion of said packing element. 45

8. In a packing assembly for a plunger, the combination of an annular resilient packing element having a sealing portion adapted to be expanded into sealing engagement with the wall of an encircling cylinder, and having an anchored portion below the sealing portion adapted to be secured to the plunger, said element being formed on its outer periphery intermediately of said aforesaid portions to define a downwardly facing annular shoulder, and a reinforcing ring encircling said element below said sealing portion adapted to engage and support said shoulder, said ring being free to adjust itself with respect to 60 the sealing portion of said element independently of the plunger. 70

GEORGE A. HATFIELD.

CERTIFICATE OF CORRECTION.

Patent No. 2,063,160.

December 8, 1936.

George A. Hatfield.

It is hereby certified that error appears in the above numbered patent requiring correction as follows: In the drawing, Figure 2 should appear as shown below instead of as in the present drawing of the patent:

Fig. 2

and that the said Letters Patent should be read with this correction therein that the same may conform to the record of the case in the Patent Office.

Signed and sealed this 23rd day of March, A.D. 1937.

Henry Van Arsdale

Acting Commissioner of Patents.
